(57) **CLAIM**

The ornamental design of a modular patch for an electronic stethoscope as shown and described.

DESCRIPTION

FIG. 1 is a top perspective view of a modular patch for an electronic stethoscope showing our new design.

FIG. 2 is a right side view thereof.

FIG. 3 is a left side view thereof.

FIG. 4 is a rear view thereof.

FIG. 5 is a front view thereof.

FIG. 6 is a top view thereof; and,

FIG. 7 is a bottom view thereof.

The broken lines depict portions of the modular patch for an electronic stethoscope that form no part of the claimed design.
